UNITED STATES PATENT OFFICE.

HERMANN LACHENMEYER, OF DUSSELDORF, GERMANY, ASSIGNOR TO COM-
MANDITGESELLSCHAFT SPIEGEL, NACKEN & CO., OF COLOGNE, GERMANY.

TROLLEY.

SPECIFICATION forming part of Letters Patent No. 665,369, dated January 1, 1901.

Application filed February 20, 1900. Serial No. 5,883. (No model.)

To all whom it may concern:

Be it known that I, HERMANN LACHENMEYER, a subject of the King of Prussia, German Emperor, residing at 64 Rosenstrasse, 5 Dusseldorf, in the Kingdom of Prussia and Empire of Germany, have invented certain new and useful Improvements in Current-
receivers for Electric Railways, of which the following is a full, clear, and exact description.

The object of the present invention is an improvement in current-receivers for electric railways with overhead power which prevents the slipping of the trolley-wheel from 15 the conductor under any circumstances.

The contrivance is essentially characterized by two parts inclosing the trolley-wheel constructed as a revolving cross provided with arms, which arms revolve by striking 20 against the transverse wires which serve to give its tension to the electric conductor when the trolley moves forward along the conductor, and thereby prevent the slipping of the trolley from the conductor under any circumstances. 25 The arms of the aforesaid parts inclosing the trolley-wheel extend some distance beyond its periphery, and the length is so regulated that as they revolve one pair of the arms of the cross always incloses the conductor which lies upon the trolley-wheel, so that the latter cannot slip in any position.

In the accompanying drawings, Figures 1 and 2 show the improvement in partially-longitudinal section and as a side elevation. 35 Figs. 3 and 4 illustrate in section and elevation a variation of the contrivance shown in Fig. 1.

On the bolt *c* of the forked rod *g* is placed the trolley-wheel *a*, the position of which is 40 fixed by the pin which fits into a groove *r* of the bolt *c*. On both sides the trolley-wheel is inclosed by the parts *b*, the arms of which project beyond the periphery of the trolley-wheel *a*. The arms are arranged crosswise, 45 so that thus each part has the form of a revolving cross. These parts are keyed to the axle and revolve with it, while the trolley-wheel naturally revolves independently on

the axle. When the arms *b* standing vertically at the top strike against the transverse wires to which the conductor is attached, the parts *b* revolve through ninety degrees. The consequence of this is that the conductor is always inclosed by the arms, and therefore slipping of the trolley-wheel is rendered impossible under any circumstances. 55

Regard must be paid to the fact that the conductor can never lie on the edges of the hollow grooved trolley-wheel *a*, as the arms *b* project over these edges, as shown in Fig. 60 1. The position of the conductor in the groove *a* is therefore by this means always established. In order to insure the position of the parts *b* in such a way that the arms may always be vertical or horizontal, a toothed 65 wheel *z* with four teeth is provided at one end of the bolt *c*, with which toothed wheel a spring-pawl *y* engages. The contrivance can also be so arranged that the parts *b* do not act as a revolving cross, but always regain 70 their original position after the revolution caused by striking against the transverse wires. This can best be attained, as shown in Figs. 3 and 4, by making two of the arms into counterpoises *b*². This latter contrivance has the advantage of simplicity, and, 75 moreover, the bolt *c* has not to revolve continuously, and thus possibly effect the working of the trolley-wheel.

What I claim, and desire to secure by Letters Patent, is—

1. In current-receivers for electric railways the combination of a trolley-wheel *a*, cruciform guards *b*, *b*, on each side of the trolley-wheel the revoluble bolt *c* on which the 85 guards *b* *b* are keyed and on which the trolley-wheel runs freely and the bifurcated trolley-pole *g* in which the bolt *c* is mounted, as shown and described.

2. The combination of the trolley-wheel *a*, 90 the guards *b* *b* formed with projecting arms *b*' and recessed faces to inclose the flanges of the wheel, the revoluble bolt *c* on which the guards *b* are keyed, and the bifurcated trolley-pole *g* in which the bolt *c* is mounted as 95 shown and described.

3. The combination of the trolley-wheel *a*, cruciform guards *b* having projecting arms *b'*, bolt *c* on which the trolley-wheel runs and on which the guards *b* are keyed, the star-wheel *z* keyed on the revoluble bolt *c* and having teeth corresponding in number with the arms *b'* and the detent-pawl *y* engaging with the star-wheel *z* and maintaining the

successive arms *b'* of the guards in vertical position as explained.

In witness whereof I subscribe my signature in presence of two witnesses.

HERMANN LACHENMEYER.
